UNITED STATES PATENT OFFICE.

JAMES A. NIMAN, OF MANSFIELD, OHIO.

DESIGN FOR IRON CORNICE AND COLUMN.

Specification forming part of Design No. 7,534, dated July 7, 1874; application filed May 25, 1874.
[Term of Patent 7 years.]

To all whom it may concern:

Be it known that I, JAMES A. NIMAN, of Mansfield, in the county of Richland, State of Ohio, have invented a Design for Iron-Work Cornice and Column, of which the following is a specification:

The nature of my design is fully represented in the accompanying photographic illustration, to which reference is made, and is presented in an arrangement of architectural construction hereinafter specified, and preferably formed of cast-iron.

The entablature of the annexed drawing is formed as follows: The cyma recta is plain; the cornice is composed of a row of acanthus leaves in *rillero*, and with the stem end below; the ovolo is plain; the cavetto of acanthus leaves arranged similar to the cornice, but of smaller size; the frieze is plain, and

furnished with spaces, surrounded by an oval border in *rillero*, within which names may be inserted. The columns are fluted shafts, with double capitals, separated by a bunch of acanthus leaves in relief, and rectangular, with central and corner flutings, double capitals, and ornamental figured crests. Above each capital is placed a bracket, fluted as shown, and near its upper end provided with the figure of a lion's head erased and in relief.

What I claim as my invention, and desire to secure by Letters Patent, is—

The architectural designs for columns, entablature, and bracket, substantially as herein shown and described.

JAMES A. NIMAN.
